SLIDING VANE ENGINE OR PUMP

Aaron C. Bradford, Thayer, Mo.

Application November 9, 1943, Serial No. 509,599

3 Claims. (Cl. 103—137)

1

This invention relates to a rotary pump or engine, and has for the primary object the provision of a device of this character which will be extremely efficient and consists of a minimum number of parts, such as a stator and a rotor including a slideable abutment or gate of an improved construction to assure against leakage between the rotor and stator and still maintain friction therebetween reduced to a minimum.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation illustrating a pump or engine constructed in accordance with my invention.

Figure 2 is a transverse sectional view illustrating the stator and rotor, the latter including the improved construction of abutment or gate.

Figure 3 is a vertical sectional view illustrating the device.

Figure 4 is a side elevation illustrating the abutment or gate.

Figure 5 is an edge elevation illustrating the gate or abutment.

Referring in detail to the drawing, the numeral 5 indicates a stator including an annular body 6 in which is formed a chamber 7 of substantially elliptical shape. The stator 5 further includes removable end walls or heads 8 provided with internal recesses 9 arranged in opposed relation and eccentrically of the chamber 7 and which provides seats for rotatably supporting a rotor 10' having wiping contact at one point with the internal wall of the body 6 of the stator 5 and between inlet and outlet ports designated generally by the characters 10 and 11.

A shaft 12 is integral with one end of the rotor 10' and extends through an opening 13 provided in one of the heads or end walls 8. A stuffing gland 14 is provided between said last-named head or end wall and the shaft 12 to prevent leakage about the shaft.

The rotor 10' includes a cylindrical body 15 provided with an elongated slot 16 extending therethrough to slidably receive an abutment or gate 17 substantially rectangular shaped, the edges of which are provided with substantially V shaped grooves 18 to accommodate packing 19 adapted to have wiping contact with the wall of

the body 6 of the stator as well as with the heads or end walls 8 to prevent leakage between the gate or abutment and the stator.

The packing 19 is substantially triangular shaped in cross section so as to tightly fit the V-shaped grooves and protrudes a limited distance beyond said grooves to have the stated wiping contact with the stator. The packing 19 is made up from a plurality of L-shaped strips, the ends of which are cut on an angle so that when the strips are assembled in the grooves of the abutment or gate the ends of the strips will overlap, as shown at 20, effecting an efficient seal between connecting or adjacent strips of the packing.

The rotor rotates within the stator and during its rotation the gate or abutment is free to slide relative thereto so that the packing thereof will maintain a wiping contact with the interior walls 20 of the stator and it will be seen that during the rotation of the rotor any fluid which may be within the chamber 7 will be forced therefrom by the abutment or gate when the latter passes beyond the outlet port and that fluid will be taken into the chamber 7 as the abutment or gate moves away from the inlet port 10, thereby permitting the fluid to be efficiently circulated by the device if the device is used as a pump and if used as a compressor or engine substantially the same operations occur.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a pump, a stator having inlet and outlet ports and forming a chamber of elliptical section and having opposite end walls and a curved side wall, a rotor eccentrically journaled in the chamber and having contact with the stator between said ports and provided with a slot, a substantially rectangular shaped plate slidable in the slot and having grooves in the edges thereof, and a packing arranged in the grooves to contact the stator, said packing taking the form of L-shaped strips to fit about the corners of said plate and having their adjacent ends beveled for overlapping, all of said edges of the rectangular plate having grooves formed therein and the beveled overlapping ends of said packing strips being disposed in the intermediate part of each of said edges, so that the packing strip portions on the

opposite side edges of the plate are disposed in contact with the end walls of the stator and of the slots in the rotor and the other packing strip portions on the other opposite side edges of the plate are in contact with the curved stator wall.

2. In a pump or the like, a stator having inlet and outlet ports and forming a chamber of elliptical section and having opposite end walls and a curved side wall, a rotor eccentrically journaled in said chamber and having contact with the curved side wall of the stator between said ports and provided with a slot having opposite end walls each flush with an end wall of the stator, a substantially rectangular plate slideable in said slot and having grooves in its edges and coacting with the interior of the chamber and including a pair of opposite edges each of which passes over said parts in succession and forming expanding and contracting fluid pumping spaces, and a packing mounted within each of said grooves, said packing taking the form of substantially L-shaped strips having their adjacent ends beveled to overlap one another and being so ar-

ranged within the groove that the beveled overlapping ends lie within the portion of said groove intermediate the walls thereof and the opposed ends fit about the complementary edges of said groove.

3. In a pump, a stator having inlet and outlet ports and forming a chamber of elliptical section and having opposite end walls and a curved side wall, a rotor eccentrically journaled in the 10 chamber and having contact with the stator between said ports and provided with a slot, a substantially rectangular plate slideable in said rotor slot and having V-shaped grooves in its edges and coacting with the walls of the pump chamber and including opposite edges each of which passes over said ports in succession, said plate forming 15 expanding and contracting fluid spaces, and a packing mounted within each of said grooves, said packing taking the form of substantially L-shaped strips having their adjacent ends beveled to overlap one another and of a cross-section conforming to a groove of said plate.

AARON C. BRADFORD.
